UNITED STATES PATENT OFFICE

CHARLES O. WOOD, OF CHAMBERSBURG, PENNSYLVANIA

MOLDER'S FLASK

Application filed July 18, 1930. Serial No. 468,943.

My invention relates to guides for molders' snap flasks that comprise the usual cope and drag and a cheek or pattern plate, or a plurality of them.

5 The invention consists in using a group of pins mounted on each end of the drag, each pin on one end of the drag cooperating with one of the pins on its opposite end, the pins being either directly opposite or 10 diagonally opposite, there being as many pairs of opposite pins as there are guided elements of the flask to be removed from the drag.

15 The improvement thus permits the successively guided elements of the flask to be removed from the drag, without influencing the other elements, as will more fully appear hereinafter.

20 Referring to the drawings in which I have illustrated the most used form of snap flask, and in which like parts are similarly designated—

Figure 1 is an end elevation of a flask embodying my invention.

25 Fig. 2 is a plan view showing the pattern in plan.

Fig. 3 is a side elevation, broken away, to show the pattern in section.

30 Fig. 4 is a side elevation of the adjusting plates and slides in reversed position to that shown in Fig. 3 with respect to the guide pins.

Fig. 5 is a plan view of an adjusting plate. Fig. 6 is a cross section.

35 Fig. 7 is a bottom view, and

Fig. 8 an end elevation of an adjusting plate shown on a larger scale.

40 Figs. 9, 10 and 11 are views similar to Figs. 6, 7 and 8 of a modified construction of adjusting plate.

Fig. 12 is a diagram showing the slides engaging directly opposite pins.

45 In Figures 1, 2 and 3 I have shown the most usual form of flask, comprising a drag D, a pattern plate P, and a cope C provided with sand strips S and their usual operating mechanism, all of which are well known.

50 In such a construction I mount on the drag D on one end thereof a group of as many guide pins as there are guided elements to

be removed from the drag, in the flask illustrated two, one guide pin at each end for the pattern plate and one at each end for the cope.

I am aware that two pins have heretofore been used at each end of flasks, but both pins 55 at each end simultaneously act to guide both removable members, i. e., both pins at each end operate to guide both the cope and the pattern plate.

In my construction the pins 15, 15^a, 15^b and 15^c are threaded on their lower ends 16, Fig. 3, into the lug 17 on the drag D, or they may have a sliding or a driving fit in a hole drilled in the drag lug and be held by a set screw 18, Fig. 4.

55 The pattern plate lugs 19 and the cope lugs 20 have an elongated hole 21, each hole passing over all the pins of a group of pins, without the sides of the holes touching them.

60 Adjusting plates 22 are fastened to the respective pattern plate and cope lugs 19 and 20. These adjusting plates are shown in detail in Figs. 4-11, and are held to the lugs of the cope and pattern plate by small bolts or screws 23 passing through holes 24 in 75 the plates which holes are slightly larger in diameter than the shanks of the bolts 23 to permit the plates to be slightly moved with respect to their guide pins.

65 Each adjusting plate has on its under side 80 a small boss 25 near one end of the member, and there are two grub set screws 26 in the plate. This arrangement of boss and set screws gives the adjusting plates 22 a three-point support on the cope and pattern plate 85 lugs to compensate for slight variations of the guide pins from a vertical.

70 Each adjusting plate has a slide 27 that partly surrounds the guide pin, here shown as nearly semi-circular, that fits against its 90 guide pin 15, 15^a, 15^b or 15^c, and that preferably projects above and below the plate. The adjusting plates for the pattern plate are omitted from Fig. 2 for clearness.

75 The slides 27 are less than a semicircle in 95 cross section, in order that they may overlap and not interfere when the removable members of the flask are placed in position or withdrawn, as shown, from closely set pins, in Figs. 3 and 4. It is immaterial on which 100

side of the pin these slides are arranged so long as the slides for the next succeeding flask member are on the opposite side of the guide pin.

- 5 In Figs. 1 and 3 the slides 27 for the cope are shown on the side of the pin toward the center of the flask, and those on the pattern plate on the opposite sides of the guide pins; while in Fig. 4 the slides 27 are shown against 10 the guide pin on the side of the pin nearest the center of the flask and those for the cope on the opposite side of the pins.

In Figs. 9-11 the adjusting plate 22^a is considerably shorter than the plate 22, the 15 slides 27 being at the extreme end of the member, and not, as in Figs. 6-8, arranged between the boss 25 and the set screws 26. The boss 25 and set-screws 26 being in these figures on the same side of the slide, and 20 but a single fastening bolt 23 is used for fastening the plate to the lug.

In Figs. 1-3 the adjusting plates and their slides are shown cooperating with diagonally opposite guide pins, the cope being guided on 25 pins 15^a and 15^b, as is indicated by line 28, while the pattern plate is guided on pins 15 and 15^c, as indicated by line 29.

In the diagram Fig. 12 each removable flask member has the adjusting plates directly opposite, as indicated by lines 29 and 30, the cope engaging directly opposite guide pins 15 and 15^b while the pattern plate is guided by the other pair of directly opposite pins 15^a and 15^c, or vice versa.

35 One (or both) pattern plate lugs 19, Fig. 1, is preferably provided with a bevel 31 for attachment of a vibrator or tapping device, so that the pattern can be vibrated and the vibration thereof not materially affect the 40 cope guide pin while the cope is being removed, so that there will be considerable relative movement between the said mold portion on the cope and the pattern during the removal of the cope.

45 The vibrations of the pattern plate are so rapid that the pattern is always clear of the sand in the cope, which is desirable in the top mold portion so as to make the pattern quite loose of the sand supported on the sand 50 strips on the cope while the cope is being removed. Any strain put on the cope guide pins is not communicated to the pattern plate pins, thereby avoiding any distortion by the pattern on the pattern plate, of the sand in 55 the drag.

By my invention, besides the above-named advantage, I obtain considerable improvement of the sand molds and flask structure, for the reason that the adjusting plates are 60 universally adjustable for each pin to coincide with the axes of their respective pins by the set screws 26, and for wear by loosening bolts 21, moving the plates against their pins, and re-clamping the plates.

65 The pattern plate is unaffected by the cope

during its removal, so that the sand mold in both cope and drag is not distorted.

The cope pins and pattern plate pins may not be perfectly parallel, but may be slightly distorted, so that when the cope is lifted the 70 spring of the cope guide pins will not move the pattern plate pins and pattern plate.

The adjusting plates for cope and pattern plate are independent of one another.

The adjusting plates can all be made alike, 75 so that one design of adjusting plate will suffice for all guide pins.

With wooden flasks and wooden pattern plates their cast iron lugs and the guide pin supporting lugs can be screwed onto them 80 not exactly normal and the adjusting plates take care of the irregularity, independent of the angle of one pair of parallel pins to the other pair, and independent of the parallelism of the pins of a pair, which is permitted 85 by the separate guidance of cope and pattern plate.

In the flask illustrated while the pins of a pair have separate functions, a plurality of pins at each end of the flask provide bearing 90 for the hands of the molder as he starts the cope and pattern plate for removal from the drag.

If the pattern plate supports the guide pins then this plate acts as the drag. This 95 might occur if the guiding means for both cope and pattern plate cooperated with the same pins.

The pins may also be of different sizes, 100 cross sections, or diameters to prevent the placing of the molds on the drag in improper order.

In those cases where one part of the pattern requires that the lift shall not be vertical the pins for that removable flask member 105 that carries the corresponding mold can be placed at the required angle. This very materially reduces the cost of patterns. It is now the practice, in such cases, to make those parts of the pattern loose from the main pattern or from the pattern plate and temporarily connect them thereto by dowels, and the loose portion remains in the sand in the removable member, to be subsequently carefully removed by the molder.

110 All these advantages result in a lesser percentage of imperfect sand molds, and greatly reduce the time required to make the molds.

It will be noted that the form of adjusting plate 22 has a hole through which a flask 115 guide pin passes, Figs. 6 and 7. This hole has a good clearance c on that side of the pin opposite the slide, to more readily place the removable flask members in position.

I claim—

1. A molder's flask comprising a drag and a plurality of superposed flask members successively removable from the drag, in combination with a plurality of guide pins at 120 each end of the flask, each removable flask 125

member being guided by different pins of said plurality of pins.

2. A molder's flask comprising a drag and a plurality of flask members removable from the drag, in combination with groups of guide pins on the drag, there being as many guide pins in a group as there are removable members, lugs on each removable member having openings therethrough to pass over each group of pins without contact therewith, an adjusting plate secured to each lug, a slide on the plate, and means to universally adjust the plate for the slide to lie against its pin, each slide cooperating with a different pin of a group.

3. In a molder's flask, an adjusting plate having a slide thereon for fitting against a guide pin, and means to secure the plate to the lug on a flask member, said plate being adjustable in all directions transversely in relation to the pin.

4. In a molder's flask, an adjusting plate having a slide thereon less than a semi-circle in cross section, a boss on the underside of the plate, and two adjusting screws in the plate, said boss and screws disposed in a triangle to furnish a three point support for the plate, and means to fasten the plate to the lug of a flask member.

5. A molder's flask, comprising a drag, a pin supporting lug at each end of the flask and a group of guide pins in each lug, a plurality of removable flask members superposed on the drag, each member having perforated lugs through which the groups of pins loosely pass, there being as many pins in a group as there are removable members, each member cooperating with a pin of each group, and adjustable slides mounted on the lugs of the removable members to closely fit and partially surround the pins.

6. In a molder's flask, an adjusting plate having a slide thereon for fitting against a guide pin, and means to secure the plate to the lug on a flask member, said plate being adjustable in all directions transversely in relation to the pin and tiltably adjustable whereby its pin engaging end may be positioned at various inclinations according to the inclination of the pin.

In testimony that I claim the foregoing as my invention, I have signed my name hereto.

CHARLES O. WOOD.
